(57) **CLAIM**

The ornamental design for a vented urine meter, as shown and described.

DESCRIPTION

FIG. 1 is a perspective view of a vented urine meter showing our new design;

FIG. 2 is an enlarged view of the circled portion "2" in FIG. 1;

FIG. 3 is a top plan view of the vented urine meter of FIG. 1;

FIG. 4 is a front elevation view thereof;

FIG. 5 is a rear elevation view thereof;

FIG. 6 is a left side elevation view thereof;

FIG. 7 is a right side elevation view thereof; and,

FIG. 8 is a bottom plan view thereof.

The broken lines depicting portions of the vented urine meter are shown for illustrative purposes only and form no part of the claimed design. The break lines in FIGS. 1 and 3-8 represent indeterminate length, and portions of the article between the break lines form no part of the claimed design.
